QUILTING FRAME

Edward G. Bartling, 3879 Hallmark Drive,
Granger, Utah 84119

Filed Mar. 3, 1975, Ser. No. 554,518

Term of patent 14 years

Int. Cl. D15—06

U.S. Cl. D15—66

FIG. 1

FIG. 2

FIG. 3

FIG. 1 is a perspective view of a quilting frame showing my new design;

FIG. 2 is a left side elevational view; and
FIG. 3 is a right side elevational view.

I claim:

The ornamental design for a quilting frame, substantially as shown and described.
